DUST AND LINT BLOWER FOR SPINNING FRAMES

Luther Y. Herren, Fayette, Ala.

Application January 18, 1950, Serial No. 139,289

6 Claims.

(Cl. 57—56)

1

This invention relates to a dust and lint blower for spinning frames, which shall be simple of construction and which may be readily installed on existing spinning frames.

The principal object of this invention is to provide means for continuously blowing dust and lint out from under a spinning frame, thereby saving the labor of a sweeper in the mill and keeping the spinning frame and floor therebeneath clear of dust and lint at all times.

Another object is to provide a blower of the character designated which shall serve to keep the flexible drive member between the cylinder and the spindles tight and at the same time rotate a fan by means of said drive member.

A further object is to provide a blower of the character designated which shall have means associated therewith for protecting the blower and other parts of the spinning frame from damage in event the flexible drive member should break.

A blower for spinning frames embodying the features of my invention is illustrated in the accompanying drawing forming a part of this application in which:

Fig. 1 is a somewhat diagrammatic transverse sectional view of a spinning frame, partly broken away, showing the blower attached to the underside thereof; and,

Fig. 2 is an enlarged plan view of the blower taken generally along line II—II of Fig. 1.

Referring now to the drawings for a better understanding of my invention I show a conventional spinning frame designated generally by the numeral 10. The spinning frame has rows of spindles 11 and 11a driven from the main cylinder 12 of the frame by means of a flexible drive member 13, such as a belt or a band. In the manner understood the cylinder is driven by a suitable motor or the like, not shown. The drive member 13 makes two or more complete turns of the cylinder 12 and drives the spindles 11 and 11a.

My dust and lint blower comprises a supporting bracket 14 which is rigidly connected to the frame 10 by means of bolts 16. Pivotedly mounted adjacent the inner end of the bracket at 17 is an arm 18 carrying a weight 19. On the inner end of the arm 18 is journaled a shaft 21 having a pulley 22 on one end thereof and a fan 23 on the other end. The flexible drive member 13 also passes around the pulley 22 and thus drives the fan 23 while the weight 19 and the weight of the fan 23 and arm 18 serve to keep said drive member tight on the pulley 22, the cylinder 12 and the spindles 11 and 11a. A grease fitting 25

2

may be provided on the end of bracket 18 through which lubricant may be supplied to shaft 21.

Rigidly secured to the supporting bracket 14 are a pair of stop members in the form of brackets 24 and 26. The stop member 24 extends upwardly of the supporting bracket 14 while the stop member 26 extends downwardly of said bracket 14. Said stop members 24 and 26 have extensions 27 and 28, respectively, on their outer ends positioned to be engaged by the arm 18 and thereby limit the upward and downward movement of the arm in event the drive member 13 should break. This limits the fan 23 and arm 18 from engagement with other parts of the spinning frame should the drive member 13 break. Should the drive member break, without such protecting arms it possibly would tangle in the pulley or fan and pull the assembly up into the frame, or if the drive member did not pull the fan up into the frame the fan would fall onto the lower frame work or floor and thereby damage the framework or fan blades.

In operation, the drive member 13 is driven by the cylinder 12 and thereby causes the spindles 11 and 11a, the pulley 22 and the fan 23 to rotate. As the fan rotates, dust, lint, or the like is blown along the length of and from under the spinning frame. The weight of the fan 23 plus the mass of weight 19 prevents the drive member 13 from slipping on the spindles, cylinder and pulley 22.

While, I show a spinning frame equipped with only one of my improved dust and lint blowers it will be apparent that, if necessary, a plurality of such blowers may be mounted in the manner disclosed on the spinning frame at intervals and driven by the cylinder 12. Also, while I show a flexible drive member in the form of a rope, it will be apparent that the blower may be driven by a tape or band drive member. Further it will be appreciated that my invention is adapted for use on spinning frames wherein a single flexible drive member drives more than two spindles, as in those cases in which each belt or band drives four spindles.

From the foregoing it will be apparent that I have devised an improved dust and lint blower for spinning frames which is simple of construction and one which continuously blows the dust, lint, or the like longitudinally and from under the spinning frame as the frame is operated. By positioning the blower on the weight arm the flexible drive member is held tight and at the same time the fan is operated by said drive member.

While I have shown my invention in but one

form, it will be obvious to those skilled in the art that it is not so limited, but is susceptible of various changes and modifications, without departing from the spirit thereof, and I desire, therefore, that only such limitations shall be placed thereupon as are specifically set forth in the appended claims.

What I claim is:

1. In a dust and lint blower for spinning frames having a driven cylinder and a spindle, 10 a supporting bracket rigidly secured to the lower portion of the frame, an arm pivotally mounted to the bracket and extending inwardly of the spinning frame, a fan having a pulley operatively connected thereto and mounted for rotation on the arm, and a flexible drive member passing around said spindle, cylinder, and pulley.

2. A dust and lint blower for spinning frames having a driven cylinder and a spindle, a supporting bracket rigidly secured to the frame at a point below the spindle, an arm pivotally mounted to the bracket and extending inwardly of the spinning frame, a pulley, a fan operatively connected to the pulley and rotatably mounted on the arm, a flexible drive member passing around said spindle, cylinder, and pulley, and stop means limiting the upward and downward pivotal movement of the arm.

3. A dust and lint blower for spinning frames as defined in claim 2 in which the means to limit the upward and downward pivotal movement of the arm comprises a pair of brackets secured to the supporting bracket, one of said pair of

5

brackets extending upwardly of the supporting bracket and the other thereof extending downwardly of the supporting bracket, and extensions on the ends of said pair of brackets disposed to be engaged by the pivotally mounted arm upon movement of the latter beyond predetermined limits.

4. In a dust and lint blower for spinning frames having a driven cylinder and a spindle, a bracket secured to the frame at a point thereon below the spindle, an arm pivotally mounted to the bracket and extending inwardly of the spinning frame, a shaft journaled adjacent the free end of said arm, a pulley mounted on one end of said shaft, a fan mounted on the other end of said shaft, and a driving band passing around said spindle, cylinder and pulley.

5. In a dust and lint blower for spinning frames having a driven cylinder and a plurality of spindles, a bracket rigidly secured to the frame below at least one of said spindles, an arm pivotally mounted to said bracket and extending inwardly of the spinning frame, a pulley and a fan operatively connected thereto and journaled for rotation on the inner end of the arm, and a flexible drive member passing around a plurality of said spindles, and around the cylinder and pulley.

6. A dust and lint blower for spinning frames as defined in claim 5 in which a weight is mounted on the pivotally mounted arm.
